UNITED STATES PATENT OFFICE.

ARTHUR W. CAPS, OF KANSAS CITY, MISSOURI, ASSIGNOR TO PHOTOSTAT CORPORATION, OF PROVIDENCE, RHODE ISLAND, A CORPORATION OF RHODE ISLAND.

PHOTOGRAPHIC COPYING MACHINE.

Application filed June 26, 1925. Serial No. 39,755.

This invention relates to a photographic copying machine, the primary object being to so construct a photographic copying machine that both sides of a sensitized sheet 5 may be presented to a projecting apparatus to enable the operator to photograph on both sides of the sheet. Specifically, the invention includes a copy-holder movable in a horizontal plane to bring successive parts 10 of the copy holder in line with the projecting apparatus, the movements of the copy holder being effective in imparting movements to a sensitized-sheet holder so that the movements of the copy holder and the 15 sensitized-sheet holder will be synchronized.

The present invention contemplates a casing, a projecting apparatus such as a camera, a reversible sensitized-sheet holder in the casing, a rectilinearly reciprocatory copy 20 holder outside the casing, and connections between the sheet holder and the copy holder so that when the copy holder is shifted to bring different parts in line with the projecting apparatus the sheet holder will be 25 reversed, it being understood that the reciprocatory movements of the copy holder are intermittent because there must be a pause between each half of a reciprocation to provide time for making the exposure. Thus 30 a novel means is provided for printing on both sides of the sensitized sheet.

The specific construction of the illustrated embodiment of my invention will be clearly understood by reference to the following description in connection with the accompanying drawing, in which

The figure is a perspective view of a copying machine constructed in accordance with my invention.

Referring now to the drawing by numerals of reference, 1 designates a casing in which is an appropriate support 2 upon which is mounted the turntable 3 of a reversible sensitized-sheet holder 4. The specific 45 construction of the sheet holder is immaterial, it being shown as comprising two standards 5 and 6 carrying a roll holder 7 in the top, and a mask 8 below the roll holder determines the effective area of the sensitized-sheet 8' which is exposed to the pro-

jecting apparatus shown as a camera 9. The specific construction of the turntable and holder constitutes the subject matter of a separate application so it is thought that it is sufficient in this application to point out 55 that the sensitized-sheet holder rotates about a vertical axis in line with the center of the projecting apparatus.

The mask 8, consisting of two panels between which the paper is fed, is rigid with the turntable 3, the turntable being provided at its periphery with teeth 3' which mesh with the teeth of the pinion 10 on the stub shaft 11 in the bearing 12 in the front panel of the casing. The stub shaft 11 extends 60 below the bearing and it is connected to a shaft member 13 by a universal joint 14, the shaft member 13 being telescopically secured in the sleeve 15 and held against 65 rotational movement with respect thereto by a lug 16 which works in the slot 17 of the sleeve. The lower end of the sleeve is connected to a stub shaft 18 in bearing 19 carried by the bracket 20 having a universal 70 joint connection 21. The lower end of the 75 shaft 18 carries a pinion 22 which meshes with a rack 23 on a rectilinearly reciprocatory copy holder. The copy holder includes a frame which is supported upon the table 25 by the supports 26 and 27, the copy 80 holder frame 24 being spaced from the table 25 so that a backing plate or board may be received in the space 28 to press the matter to be copied against the transparent panel 29 of the copy holder. The board for pressing 85 the sheets to be copied against the transparent panel 29 may have springs 30 on it similar to springs on a blue printing frame. The construction of the copy holder, however, is not important so I do not wish to be 90 limited to any particular form of the copy holder. The copy holder is held rigid with the table but it is adapted to swing on the hinge supports 27 for the purpose of introducing and removing the sheets to be copied. 95

The rack, it will be observed, is rigid with the table 25, the table being movable rectilinearly by the operator who may slide the table along the channel guides 31 and 32. The table 25 has depending lugs 33, one at 100

each corner, and each pair of lugs supports a rod or shaft, these shafts being indicated at 34 and 35. They carry on their ends rollers 36 which ride in the channel-shaped guides 31 and 32 so that the table may easily be moved first in one direction and then in the other.

It will be observed that there is but a single projecting apparatus or camera and 10 that the problem is to expose both sides of the sensitized sheet 8' to the single projecting apparatus. One half of the copy holder will be exposed at each operation, for example, if the parts are in the position 15 shown in the drawing and the left half of the copy holder is being projected photographically against the sensitized sheet, the half to the right will be the next part projected into the casing 1. When the 20 copy holder is shifted from right to left to bring the right half of the copy holder in line with the prism 37 of the projecting apparatus 9 the rack 23 will turn the pinion 22 and through it cause the connecting shaft 25 consisting of the members 13 and 15 to turn, imparting movement to the pinion 10 so as to turn the turntable 3, 180 degrees about its axis to present the opposite side of the sensitized sheet to the projecting apparatus. 30 Then when the exposure is made the right half of the copy in the copy holder will be exposed against an unexposed side of the sensitized sheet. Consequently, both sides 35 of the sensitized sheet may be exposed, and by reason of the connection between the copy holder and the sensitized-sheet holder it will be impossible to expose one side of the sheet more than one time. That is, there can be no double exposure due to the 40 fact that the sensitized-sheet holder has been reversed, because the act of shifting the copy holder will of necessity cause the sheet holder to be reversed. Of course when the copy holder moves over its guides the motion 45 must always be communicated to the turntable on account of the positively geared connections.

In actual practice the sheet of sensitized material is fed through the mask and cut 50 off in lengths which may drop to the bottom of the casing so that they may be conveniently collected and developed. The specific form of the sheet severing mechanism is immaterial to the present invention. The 55 table 25 may be raised and lowered upon the guides 38 and 39 to properly focus the copy holder, so for that reason I have made the shaft connections between the copy holder and the sensitized-sheet holder extensible, this being accomplished by the arrangement consisting of the members 13 to 60 16, both inclusive.

In so far as the generic embodiment of 65 my invention is concerned the device is susceptible to different constructions, so I do

not wish to be limited to the exact details of construction shown.

Of course it will be understood that the amplitude of movement of the copy holder is fixed so that when the copy holder has 70 moved far enough in one direction to reverse the sensitized-sheet holder it will then be moved back in the opposite direction.

What I claim and desire to secure by Letters-Patent is:—

75

1. In a photographic copying machine, a casing, object-projecting means associated with the casing, a sensitized-sheet holder within the casing having means for exposing two sides of the sheet, a rectilinearly reciprocatory copy holder outside the casing associated with the projecting apparatus, and means connecting the copy holder and the sheet holder for causing reversing movements of the sheet holder in response to reciprocatory movements of the copy holder. 80

2. In a photographic copying machine, a casing, object-projecting means associated with the casing, a sensitized-sheet-holder within the casing having means for exposing two sides of the sheet, an intermittently reciprocatory copy holder outside the casing associated with the projecting apparatus, and means connecting the copy holder and the sheet holder to cause reversing movement of the sheet holder when the copy holder is moved in either of two directions. 90

3. In a photographic copying machine, a casing, object-projecting means associated with the casing, a sensitized-sheet holder within the casing mounted for reverse movements so that two opposite sides of the sensitized sheet may be exposed to the projecting apparatus, a copy holder outside the 100 casing movable rectilinearly in a plane transverse to the axis of the projecting means, and driving connections between the copy holder and the sensitized-sheet holder to synchronize their movements. 105

4. In a photographic copying machine, a casing, object-projecting means associated with the casing, a vertically disposed, reversible sensitized-sheet holder within the 110 casing, an intermittently reciprocatory copy holder outside the casing, and connections between the copy holder and the sensitized-sheet holder whereby upon movement of the copy holder, a reversing movement will be imparted to the sheet holder. 115

5. In a photographic copying machine, a casing, object-projecting means associated with the casing, a vertically disposed, sensitized-sheet holder in the casing rotatable about a fixed axis having an annular row of gear teeth thereon, a reciprocatory copy holder outside the casing having a rack bar, a pinion engaging the rack bar, a pinion engaging the teeth on the sheet holder, and a shaft connected to the pinions. 120

125

6. In a photographic copying machine, a casing, object-projecting means associated with the casing, a vertically disposed, sensitized-sheet holder in the casing rotatable about a fixed axis having an annular row of gear teeth thereon, a reciprocatory copy holder outside the casing having a rack bar, a pinion engaging the rack bar, a pinion engaging the teeth on the sheet holder, a shaft and universal joints between the shafts and the pinions.

7. In a photographic copying machine, a casing, object-projecting means associated with the casing, a vertically disposed, sensitized-sheet holder in the casing rotatable about a fixed axis having an annular row of gear teeth thereon, a reciprocatory copy holder outside the casing having a rack bar, a pinion engaging the rack bar, a pinion 20 engaging the teeth on the sheet holder, a shaft comprising telescopic members, connections between the ends of the shaft and the pinions, and means for vertically adjusting the copy holder.

25 8. In a photographic copying machine, a sensitized-sheet holder comprising a vertically disposed sheet supporting member, a turntable at the bottom of the member having gear teeth on its periphery, a reciprocatory copy holder, a rack on the copy holder, pinions engaging the teeth on the turntable and the teeth of the rack, and a shaft connecting the pinions.

35 9. In a photographic copying machine, a sensitized-sheet supporting member, a turntable supporting the member having gear teeth on its periphery, a pinion engaging the teeth, a copy holder spaced from the turntable comprising a frame, a table supporting the frame, a rack on said copy holder, a pinion meshing with said rack, guides for the table whereby the table may move back and forth to rotate the pinion meshing with the rack, and a shaft connecting the pinion engaging the teeth on the turntable and the pinion engaging the rack.

40 10. In a photographic copying machine, the combination with a camera casing, a sensitized sheet holder arranged in the focal plane thereof, mechanism for reversing the sheet holder, and image projecting means associated with the casing embodying a lens and prism, of a copyholder arranged outside of the casing in a plane angular to the 45 focal plane, supporting means for the copyholder upon which it is movable to present successive image areas to the lens and driving means connecting the sheet holder reversing mechanism and the copyholder for 50 synchronous movement.

60 In testimony whereof I affix my signature.

ARTHUR W. CAPS.
